UNITED STATES PATENT OFFICE.

FRANCIS M. ELLIS, OF OAK PARK, ILLINOIS.

ANCHOR OR TIE FOR BUILDING CONSTRUCTIONS.

1,301,668.

Specification of Letters Patent. Patented Apr. 22, 1919.

Application filed May 25, 1916. Serial No. 99,741.

To all whom it may concern:

Be it known that I, FRANCIS M. ELLIS, a citizen of the United States, residing in the village of Oak Park, county of Cook, and 5 State of Illinois, have invented certain new and useful Improvements in Anchors or Ties for Building Constructions, of which the following is a specification.

My invention relates to anchors or ties 10 for building construction, and is particularly designed and adapted for securing frames and other wooden parts in fixed relation to hollow tiles used in the exterior and interior walls of many present day 15 buildings.

The principal objects of these improvements are to provide a simple form of anchor or tie, which is strong and durable, cheap in manufacture, of light weight, easy 20 of application, and effective in securely holding frame parts or other wooden structures in their desired position with respect to hollow tiles used in building construction. A particular object is to provide means where- 25 by such contiguous parts may be drawn tightly and firmly together, and in such cases as window frames, so tightly that objectionable air and weather are excluded; and also to provide a tie which will be completely 30 hidden from view when the building is finished. Other objects and advantages will appear hereinafter.

In the accompanying drawings, which form a part of this specification, I have illustrated a preferred form of these improvements and some of the applications thereof in construction work involving tiles, to which class of work it is peculiarly adapted. In these drawings Figure 1 is a fragmentary 40 sectional top view of a window frame secured by my improved tie to tiling comprising the building wall;

Fig. 2 is a fragmentary face view of the structure of Fig. 1, part of the inside casing 45 being broken away;

Fig. 3 is a fragmentary vertical section of the lower part of a window frame showing the application of the improved tie thereto;

Fig. 4 is a fragmentary sectional view of 50 two tiles with the tie held in surface recesses thereof;

Fig. 5 is a perspective view of the preferred form of my improved tie; and

Fig. 6 illustrates an ordinary staple pref- 55 erably employed with the tie.

My improved anchor or tie comprises pref-

erably a button-like head or anchor proper, preferably in the form of the plate 7, preferably rectangular, and preferably of fairly stiff, yet light weight sheet iron. In the 60 preferred form it is punched with the two holes 8 through which the legs 9^a of the substantially U-shaped piece of wire 9 are passed. In practice the ties are made with longer or shorter legs 9^a and with larger or 65 smaller anchoring heads 7 according to the particular use to be made of them at any given place; but for ordinary purposes the dimensions of the plate 7 are suitably about $\frac{5}{8}$ of an inch by $\frac{3}{4}$ of an inch with a thickness of say $\frac{3}{16}$ of an inch, and the wire part 70 75 9 is suitably about $\frac{1}{16}$ of an inch in diameter and is of soft iron capable of being bent or twisted to a considerable extent without breaking.

In Fig. 1 the wall of the building will be understood to comprise a plurality of hollow tiles, as 10, having the air spaces 11, and undercut recesses, as 13, on the four sides for retaining plaster and cement. Such hollow 80 tiles having the plaster-retaining recesses are of well known constructions and require no more detailed description. The window parts shown comprise the jamb 14, the sashes 15 and 16, the sill 17, the outer casing 18, 85 the inner casing 19 and the jamb-spacing piece or furring 20, all assembled and secured together, as by nails 21, and providing the chamber 22 for counterpoise weights for the sashes 15 and 16. 90

It is pointed out that in some constructions the tiles adjacent to the window frame are provided with projections respectively similar in shape and relative position to a cross section of the furring 20, such projections serving to space the jamb from the tiles to provide a wall or chamber, as 22, for the counterpoise weights. By my present construction in employing the furring 20 I avoid the extra expense of such special tiles, 100 and provide a rigidly secured piece of wood upon which other window parts may be readily and firmly secured. 95

Owing to the fact that nails and the like holding means cannot be driven into the 105 hard tiles it has been exceedingly difficult to fasten window frames and the like securely in the desired position, and I am not aware of any method or device hitherto suggested by which the same is effectively and satisfactorily done. According to these improve- 110 ments, however, I am able to secure the

frame parts in position not only exceedingly rigidly so as to provide a very strongly and firmly set frame, but also so as to have a structure through which the wind and weather will not find entrance to the interior of the house, this latter being a very serious objection to the hitherto methods of securing such frames. The construction work is also rendered easy and rapid.

10 While the tiles, as 10, Fig. 1, are being laid along the sides of the window frame, and also in some cases at the time the tiles upon which the sill rests are laid or when the frame is positioned thereon, as well as when 15 tiles are laid on top of the frame, the improved ties or anchors are positioned with the head or button, as 7, against inner surfaces of a tile or tiles and the wire legs 9^a projecting therefrom into proximity with 20 the frame or other part to be held.

In the case of the anchor or tie which I will denominate A, Fig. 1, the builder, having set the window frame and stayed it in its desired position, places the ties between the tiles preferably as illustrated, so that the legs 9^a project close to the edge of the casing 18. In the case of the tie B, Fig. 1, I prefer to position the tie directly in the corner of the tile, as illustrated, the wires 30 9^a thus leading directly to the corner of the jamb-spacing piece or furring 20 the legs 9^a being ultimately entirely covered by the casing 19.

Suitable auxiliary anchoring means, such 35 as a nail or staple, as S, are driven firmly into the part to be secured. The staple is preferred, both for its strength and for its function of holding one of the wires securely during the twisting operation, as well as 40 after the twisted legs are bent down to be covered by the plaster. The staple straddles one of the legs 9^a and is "driven home." The ends of the two legs of the wire are then twisted together by means of pliers, 45 and this twisting is continued until the part to be secured, as the casing 18, is brought snugly and tightly and firmly down, as upon the tile 10, whereupon the twisted ends of the wires are bent toward the tile so that 50 when the stucco or other plaster facing 23 is applied, the tie will be completely covered and there will be no appearance of the means employed for securing the frame in place. In the case of the tie B the staple 55 S is driven into the furring 20 holding one of the legs 9^a, whereupon the two legs of the tie are twisted together and the frame is bound tightly against the tile 10. The frame is thus held by ties on the outside as 60 well as on the inside of the wall. The interior casing 19 is not applied until after the plaster 24 has been put on, when it may be nailed upon other frame parts as shown.

The parts shown in Fig. 3 comprise the 65 sash 16, stool 25, sill 26, apron 27, furring

28, tile 10, and facing 29. The head 7 of the tie is suitably positioned in the corner of the tile and the staple is driven into the furring 28, the wire legs 9^a being twisted together and ultimately covered by the 70 facing 29.

An important advantage of the present anchor or tie is that it may be employed in a large variety of situations and for many purposes, such as for holding door and window frames, moldings, hand rails for porches, etc. A peculiar advantage exists in the fact that the tie may be anchored in the recesses or channels 13, as illustrated in Fig. 4, it being only necessary, in the 75 form of tie illustrated, to hold the anchoring head, as 7, in one hand and bend the wire legs 9^a at the head piece 7 so that this head piece will be at the desired angle according to the depth of the grooves or 80 recesses 13, it being possible to lock the device in quite shallow grooves.

As the head 7 is not rigid with the wires 9^a in the preferred construction it automatically adjusts itself to irregularities of the 90 surface or surfaces against which it is brought to bear, the ready bending of the wires also contributing to its finding a firm seat or anchorage in all practical situations. In most instances the head 7 will rest simultaneously against inner surfaces of two contiguous tiles, but if, due to overlapping of tiles, such inner surfaces are not in substantially the same plane, the head 7 may be turned at an angle so that one edge will 95 100 contact such inner surface on one tile while the opposite edge of the head 7 impinges against the overlapped portion of the contiguous tile.

The twisting of the wire legs, as 9^a, draws 105 the parts powerfully together and an exceedingly tight and solid structure is formed. I find also that objectionable warping of the jamb 14 owing to the presence of mortar and other dampness on the 110 tile side thereof is effectively prevented by the rigidity with which the frame is held by the ties.

Modifications may be made of the improvements herein illustrated and described 115 without departing from the spirit of the disclosure made, and reference should be had to the appended claims to determine the scope of the invention herein set forth.

I claim:

1. An anchor or tie for securing wood-work to tile construction comprising in combination a head of substantially flat metal having two holes therethrough and a substantially U-shaped wire having the legs 125 thereof in said holes, the bend in said wire lying close to said head and holding the head loosely whereby it may adjust itself against various retaining surfaces on inside portions of contiguous tiles, both legs of 130

said wire extending from one side of said head, said wire being of tough, strong, and readily flexible metal capable of having the two end portions twisted upon each other 5 against the resistance of a retaining element in the woodwork, substantially as set forth.

2. In building construction, the combination of hollow tile wall construction, wood-work such as a window or door frame part 10 adjacent to said wall construction, an anchor comprising a head piece and a pair of wire

legs connected to and extending therefrom, said head lying against an inside portion of said hollow tile, a staple or the like in said woodwork, said wire legs being twisted 15 upon each other and forming a loop engaging said staple or the like whereby the woodwork is drawn and held tightly in rigid association with said wall construction.

FRANCIS M. ELLIS.
